CLAIM

The ornamental design for a human claw machine as shown and described herein.

DESCRIPTION

This application is related to the following commonly owned co-pending patent applications: U.S. application Ser. No. 29/945,108, entitled "Human Claw Machine"; and U.S. application Ser. No. 29/945,111, entitled "Human Claw Machine".

FIG. 1 is a perspective view of a human claw machine of our new design.

FIG. 2 is a front view of the human claw machine of FIG. 1.

FIG. 3 is a rear view of the human claw machine of FIG. 1.

FIG. 4 is a first side view of the human claw machine of FIG. 1.

FIG. 5 is a second side view of the human claw machine of FIG. 1.

FIG. 6 is a top view of the human claw machine of FIG. 1; and,

FIG. 7 is a bottom view of the human claw machine of FIG. 1.

The broken lines in the drawings illustrate portions of the human claw machine that form no part of the claimed design.
